US0D1106861S

(12) United States Design Patent (10) Patent No.: US D1,106,861 S
(45) Date of Patent:  Dec. 23, 2025

(54) EARRING

(71) Applicant: AHKAH Co., Ltd., Tokyo (JP)

(72) Inventor: Mitsuyoshi Shinohara, Tokyo (JP)

() Term: 15 Years

(21) Appl. No.: 35/523,941

(22) Filed: Feb. 7, 2024

(80) Hague Agreement Data

Int. Filing Date: Feb. 7, 2024

Int. Reg. No.: DM/235151

Int. Reg. Date: Feb. 7, 2024

Int. Reg. Pub. Date: Feb. 7, 2025

(51) LOC (15) Cl. 11-01

(52) U.S. Cl.

USPC D11/41

(58) Field of Classification Search
